DESIGN FOR A PIPE THREADING MACHINE

Gilbert J. Sellmeyer, Indianapolis, Ind.

Application October 25, 1943, Serial No. 111,493

Term of patent 14 years

To all whom it may concern:

Be it known that I, Gilbert J. Sellmeyer, a citizen of the United States of America, residing at Indianapolis, in the county of Marion and State of Indiana, have invented a new, original, and ornamental Design for a Pipe Threading Machine, of which the following is a specification, reference being had to the accompanying drawings, forming a part thereof.

In the drawings:

Figure 1 is a front elevational view of a pipe threading machine embodying my new design,

Figure 2 is a rear elevational view of the same,

Figure 3 is a side elevational view of the same, and

Figure 4 is a top plan view of the same.

I claim:

The ornamental design for a pipe threading machine as shown.

GILBERT J. SELLMEYER.
